UNITED STATES PATENT OFFICE.

ORIN WEHOSKEY, OF PROVIDENCE, ASSIGNOR OF ONE-HALF HIS RIGHT TO
BENJAMIN F. ARNOLD, OF WESTERLY, RHODE ISLAND.

IMPROVEMENT IN STEAM-BOILERS.

Specification forming part of Letters Patent No. 127,394, dated May 28, 1872.

Specification describing certain Improvements in Steam-Boilers and Heaters, invented by ORIN WEHOSKEY, of the city and county of Providence, in the State of Rhode Island.

This invention consists in making, of horizontal sections bolted together, a boiler for generating steam for power or heating purposes, and for heating water for warming buildings by circulation, the sections being made in the shape of wheels with hollow hubs and arms, and double rims, also hollow, the openings between the two rims forming return flues from the top of the boiler to a circular space at the lower end, to which the smoke-pipe is attached, to carry off the products of combustion.

Figure 1 shows a front elevation of the boiler. Fig. 2 is a vertical section taken through the centre in direction of line $x x$, Fig. 3. Fig. 3 is a top view, with the upper part of the smoke-cap removed. Fig. 4 is a top view of one of the sections.

The boiler is made up of the sections A A and A', each section A being made in the shape of a wheel with a double rim, and intended to be cast in one piece, the arms and double rim being made hollow and opening into each other, and the hub with a hole through it into which all the arms open. In section A' the arms and hub are left out to form a space to be used for a fire-box. The sections are put one on top of another, in number according to the size of the boiler required, and are held together by the vertical bolts $s s$ passing through the hubs and rims of the sections. The holes in the sections through which the bolts pass are made enough larger than the bolts to allow a free circulation of the water from one section to another. Section A', which forms the base of the boiler, rests on the ash-pit D, and projects out over it so as to form the chamber B, to which the smoke-pipe is attached. The sections are placed upon each other in such order that the openings $a a$, between the outer and inner rims, shall come directly over the same openings in the next section, and thus form a continuous opening or flue from the top of the boiler to the chamber B, down which the draught passes after going from the fire up between the

arms of the sections, thus adding largely to the heating surface and increasing the efficiency of the boiler with economy of fuel. G is the fire-grate. N is a door to the fire-box made through the section A'. o o are apertures for gauges or water-cocks. The boiler may readily be enlarged by the addition of more sections, and in case of an accident or defect in one of the sections, it can easily be removed by unscrewing the bolts, and another put in the place of it. The sections are made with lips projecting around the holes for the bolts, which, being beveled off by planing or otherwise, form the joints between the sections.

The outside of the boiler is not necessarily round, as it may be made with more or less sides, and still be the same in construction and mode of operation, which is as follows: The fire being made on the grate G, the flame and smoke will pass up between the arms of the sections, which are placed so as to alternate, and detain the draught, that its heat may be absorbed by the metal and contents of the boiler. After reaching the top the draught is conducted to the chamber B by the flues $a a$, which are surrounded by water-chamber, so that all the available heat is absorbed from the draught before it reaches the smoke-pipe. The section A' has its whole inside surface exposed to the fire, and the outside of the whole boiler is protected from radiation by the smoke-jacket g.

I am aware that steam-boilers and heaters have been made in sections of various patterns and shapes; but

What I claim as my invention is—

A steam-boiler or heater composed of horizontal sections made in the shape of wheels with hollow spokes radiating from hollow hubs, and double rims, constructed and connected substantially as herein shown and described, the spaces between the rims forming return-flues from the top of the boiler to the chamber B at the bottom, for the purpose specified.

ORIN WEHOSKEY.
